GAMING DEVICE

Edward L. Garrett, Zanesville, Ohio

Application August 30, 1940, Serial No. 354,885

3 Claims. (Cl. 273—145)

The present invention relates to a gaming device. More particularly, it has to do with a gaming device for effecting agitation of game elements such as dice adapted to be used in connection with the playing of a game.

An object of the present invention is to provide a gaming device which holds a plurality of separated game elements in full view at all times of the players and which upon operation by the player will positively shift the faces of such elements to different positions and expose different groups of numbers.

Another object of the present invention is to provide a gaming device which is of the oscillatory type and which is so constructed that it is impossible for a player to control the tumbling of the separated game elements supported therein.

Another object of the present invention is to provide a gaming device wherein a plurality of separated game elements in a box are agitated by oscillatory movement and can not be touched by the hands of the player.

A further object of the present invention is to provide a gaming device which is simple and compact in structure, and which can be assembled as a part of a game board.

A still further object of the present invention is to provide a gaming device wherein the different groups of numbers upon the respective faces of a plurality of separated game elements denote the acts of the players.

Other objects and features of novelty will be apparent from the description taken in conjunction with the drawing in which—

Figure 1 is a plan view of the gaming device according to the present invention.

Figure 2 is a vertical sectional view taken on the line 2—2 of Figure 1.

Figure 3 is an end sectional view taken on the line 3—3 of Figure 2.

Referring to the drawing, the numeral 10 designates a base in which are fixedly mounted upstanding spools 11 and 12, the said spools supporting a resilient member 13. The resilient member may be made of rubber, spring steel and the like, and is preferably in the form of a continuous band. As shown in the drawing, the resilient member is in the form of continuous band extending from spool 11 to spool 12 and is mounted upon the spools in such manner that its front and back faces are in a vertical plane with respect to the base 10.

Positioned upon the resilient member 13 at a point intermediate the spools 11 and 12 is a box

14. The box 14 comprises a flat bottom plate 15 and a top bowl-shaped portion 16 mounted thereon. The bowl portion 16 consists of opposing sides and top which are transparent and ends which are non-transparent. As shown in Figures 1 and 2, the part of the bowl portion constituting the opposing sides and top are made of reticulated screening. It is to be understood, however, that any transparent material other than such screening may be employed.

Disposed within the box 14 intermediate the non-transparent end plates 17 and 18 are a plurality of partition members or plates 19, 20, and 21, suitably spaced from each other so as to form 15 a series of non-communicating compartments 22, 23, 24, and 25. Enclosed within each of compartments 23, 24, and 25 is a single game element 28 such as the conventional dice while within the compartment 22 are a pair of such game elements.

Projecting from the under face of the bottom plate 15 at a point adjacent an end thereof are a pair of opposing brackets 26, Figures 2 and 3, which engage the lower edges of the resilient member 13. The positioning of the brackets is so arranged that the upper and lower edges of the flexible member will be retained between the space defined by the brackets and the under face of the plate 15. Adjacent the other end of the bottom plate 15 and projecting from the under face of said plate are also a pair of opposing brackets 27, although only one of such pair is shown, which likewise engage the lower edges of the resilient member 13. By this means the box 30 14 is so supported upon the resilient member 13 as to admit of oscillation of the box to agitate the game elements in all of its compartments.

In playing the game employing the gaming device of the present invention, any number of 40 persons can play, and chips or the like are used, each player contributing a certain number to the "pot." The players in turn then cause the agitation of the box. This is effected by the player placing a hand upon the top of the box 45 and pulling the top forwardly and downwardly to a point adjacent the face of the base 10, and then abruptly releasing his hand from contact with the box. With the release of the box the dice within the respective compartments are agitated by the edges or corners engaging the sides of the compartments. When the box reaches a state of rest the groups of numbers turned up upon the respective faces of the dice in all of the compartments denote the acts of the players. The total number appearing on the pair of dice 50 55

in the compartment 22 indicate the number the player must obtain again on the same turn of play to win the "pot." The number appearing on the single die in compartment 23 indicates to the player the number of additional flips or agitations of the box he is entitled to on the same turn of play to obtain his number again. If he obtains such number again within such designated numbers of flips, he wins the "pot." However, before the player proceeds to flip the box to attempt to obtain the number again he must first place the number of chips in the "pot" corresponding to the number appearing on the turned up face of the single die in compartment 24, and simultaneously each of the opposing players must place a number of chips in the "pot" corresponding to the number appearing on the turned up face of the single die in compartment 25. If the "pot" is not won by the player, the chips already in the "pot," as a result of the play just completed, remain in the "pot," and are added to on the next succeeding turn of play by another of the players.

Although only one modification of the gaming device embodying the invention has been shown and described, it is to be understood that various changes and modifications may be made herein without departing from the spirit of the invention and scope of the appended claims.

Having fully described my invention, what I claim as new and desire to secure by Letters Patent is:

1. In a gaming device, a support embodying a base, and a pair of upstanding spools suitably spaced from each other and fixedly mounted in said base, a box having transparent sides, partition members spaced from each other and disposed within said box so as to subdivide said

parts, a game element in each of said compartments, and a resilient member extending between and anchored at its opposite ends on said spools for supporting said box so as to admit oscillation of the latter to agitate the game elements in all of said compartments.

2. In a gaming device, a support, a pair of upstanding spools suitably spaced from each other and fixedly mounted in said support, a box having transparent sides, partition members spaced from each other and disposed within said box so as to subdivide said box into a series of non-communicating compartments, a game element in each of said compartments, a resilient member embodying an endless band extending horizontally between said spools and supported thereon, and means on said box engaging said band at points intermediate said spools for supporting said box to admit oscillation of the latter to agitate the game elements in all of said compartments.

3. In a gaming device, a support, a pair of upstanding spools suitably spaced from each other and fixedly mounted in said support, a box having transparent sides, partition members spaced from each other and disposed within said box so as to subdivide said box into a series of non-communicating compartments, a game element in each of said compartments, a resilient member embodying an endless band extending edgewise horizontally between said spools and supported thereon, and brackets projecting from the bottom of said box engaging said band at points intermediate said spools for supporting said box to admit oscillation of the latter to agitate the game elements in all of said compartments.

EDWARD L. GARRETT.
